UNITED STATES PATENT OFFICE.

BRERETON BURGESS ROBERTS, OF CIMLA, NEATH, WALES.

SAFETY-CLUTCH FOR MINE-CAGES.

1,072,362.

Specification of Letters Patent.

Patented Sept. 2, 1913.

Application filed April 29, 1912. Serial No. 693,906.

To all whom it may concern:

Be it known that I, BRERETON BURGESS ROBERTS, a subject of the King of Great Britain, and a resident of Neath, Wales, whose post-office address is Park House, 5 Cimla, Neath, in the county of Glamorgan, Wales, have invented Improvements in Safety-Clutches for Mine-Cages, Lifts, and the Like, of which the following is a specification.

This invention relates to automatic safety devices as applied to mine cages, lifts and the like, of the kind in which gripping or scotching members adapted to engage with 15 the guides, but normally restrained from action by the tension of the winding rope, become automatically operative under the action of springs upon the tension being removed through the breaking of the rope.

20 My invention is chiefly applicable to mining cages in which guide ropes are used. Usually each cage is provided with two or more projecting guide-brackets loosely inclosing the guide ropes as the cage is drawn 25 up or let down the shaft. These guide ropes are made of strands of steel wire. They are firmly secured at the top of the shaft, and are kept in a state of tension. The cage is suspended from the hook or 30 ring of the winding rope by means of chain bridles secured to the four top corners of the cage.

Many devices have been proposed for 35 gripping the guide ropes automatically in the event of the breaking of the winding rope and so preventing the falling of the cage. In most of these the gripping device is adapted to clutch the guide ropes under the action of a spring which is normally 40 restrained by the tension of the winding rope. In some cases the device is mounted on a supporting plate loosely connected with the cage.

45 My invention is of the latter class and its advantages consist in an improved form of gripping device in combination with the member or members forming the connection between the supporting plate and the cage.

The accompanying drawings show the invention as applied to a cage with one pair of guides and guide ropes.

50 Figure 1 is an elevation of the upper part of a suspended cage with my automatic gripping device in its retracted position. 55 Fig. 2 a detail in perspective of the collar

and its connections. Fig. 3 is a plan view of the invention shown in Fig. 1.

To the top of the cage A centrally projecting upward is fixed a rod B of sufficient strength to support the weight of the cage and its load if required. The upper part of this rod has a thickened portion or shoulder C and above this is a still thicker portion D forming a head. The rod B before being attached, is pressed downward centrally through lever operating means in the form of a block E which has a hole F large enough to receive the stem but not large enough to admit the shoulder C, then through a hole G in a plate H and finally 70 through a hole I in a central part of the cage roof, when it is firmly secured by means of nuts K, the end being threaded for the purpose. The plate H is the bed of the automatic gripping device and its 75 connections. A pair of jaws L are pivotally mounted above the carrier or plate H so as to open laterally under the influence of a compressed spring M recessed between them. The jaws are raised slightly above 80 the level of the plate face by means of blocks or steps O, one at each end (the outer one not shown). Through the inner ends of these blocks, and through the plate H are passed bolts N which form the pivots of the jaws L and are well secured by nuts or riveting. Over the outer ends of the jaws L is placed a strong bridge or staple P the ends of which are passed 85 through the plate H and riveted beneath. This staple allows sufficient lateral play to 90 the jaws L but prevents any vertical displacement. Before the staple is fixed in position however the plate H, which has a recess or slot R cut in each end, is placed 95 so that the guide ropes lie loosely within the said slots; the ropes are thus retained in the slots when the staples are fixed. The jaws are conveniently recessed at the part 100 where they grip the guide-rope and the recesses are preferably rifled so as to fit closely around the wire strands. Sliding collars S are placed over the jaws L and the outer shape of the latter is such that 105 when a collar is slid in an outward direction it wedges the jaws inward so as finally to grip the rope. The reverse action allows them to open under the action of the spring M. The collar S is connected by rods U with the top bar V of a rocking frame with 110

sides W of which the lower bar Y is pivotally mounted on bearings X. The top bar V of the frame is connected with the block E by means of a rod Z, the inner end 5 of which is pivoted within a vertical slot in the side of the block.

The cage A is suspended normally from the ring a of the winding rope b by means of the bridles c attached to the lugs d of the 10 cage. The block E with its connections including the bed plate H is suspended from the same ring by chains e attached to eyes f fixed to the block. The length of these 15 chains is so adjusted that when the cage is suspended the block E is drawn up so as to just butt against the thick part C of the rod B and a slight space is preferably left between the bottom of the plate H and the top of the cage. A coiled spring g in a state of 20 compression but not strong enough to lift the cage is placed over the shoulder C between the head D and the top of the block E.

The action of the apparatus will now be apparent. When in a normal state of suspension, the parts arrange themselves as 25 shown in Figs. 1 and 2, the collars S being drawn inward, the jaws L consequently open, the plate H raised above the top of the cage, and the spring g compressed between the weight of the cage and the tension 30 of the winding-rope. Instantly upon the snapping of the winding-rope b, the cage and whole apparatus begin to fall; the part which moves downward most quickly however is obviously the block E, owing to the 35 downward push of the spring g which is now free from compression, and this acting on the toggle-like arrangement of rods Z U forces the collars S to slide outward and 40 bind the grips L upon the ropes Q before the cage has had time to fall through an equal space. By the time the weight of the cage comes upon the block, that is when the shoulder C overtakes the block, in doing 45 which it re-compresses the spring g, the grips are already in position to bear the shock which has been mitigated by the resistance of the spring g, and the only effect will be that the collars S will be driven 50 still farther under the action of the toggles and the binding of the grips be made still more effective; the rifling of the recesses in the jaws L will prevent downward slipping or it may produce a twist in the rope for a 55 short time which will act as a gradual brake; the cage will thus be left suspended by means of the rod B. I may modify the arrangement in various ways. For example the rocking frame W may be dispensed with, by uniting the rods U directly with the rods Z. Also the gripping device may, if preferred, be fixed below the plate H by providing suitable perforations therein for the connecting members. It is ob- 60 65

65 vices need not be limited to one pair, as another pair could be connected crosswise with the same block, or two supporting rods might be fixed to the top of the cage with two sets of locking gear each engaging a 70 separate pair of guide ropes. 70

Having thus described my invention what I claim is:—

1. An automatic safety device for mine 75 cages, lifts, and the like, comprising guide ropes, a movable plate, a pair of jaws mounted at each end thereof and adapted to grip the guide ropes, slideable collars adapted to cause said jaws to grip said guide ropes, a spring adapted to impel said sliding collars, said spring being normally restrained by tension of the winding rope, a connection between said movable plate and the cage consisting of a rod projecting upward from the cage, and passing loosely through the said plate, a block through which said rod also passes, and rods connecting said block with the aforesaid collars, said rod having a shoulder at its upper end to retain said block. 80

2. An automatic safety device for mine 85 cages, lifts, and the like, comprising guide ropes, a movable plate, a pair of jaws mounted at each end thereof, and adapted to grip the guide ropes, slideable collars 90 adapted to cause said jaws to grip said guide ropes, a spring adapted to impel said sliding collars, said spring being normally restrained by tension of the winding rope, a connection between said movable plate and the cage consisting of a rod projecting upward from the cage, and passing loosely through the said plate, a block through which said rod also passes, rods connecting 95 said block with the aforesaid collars, said rod having a shoulder at its upper end to retain said block, said spring actuating the aforesaid collars being mounted near the upper end of said rod, said rod having a head between which and the block, the 100 spring is normally compressed, a ring on the winding rope, and a bridle for suspending said block from said winding rope. 105

3. An automatic safety device for mine 110 cages, lifts, and the like, comprising guide ropes, a movable plate, a pair of jaws mounted at each end thereof and adapted to grip the guide ropes, slideable collars adapted to cause said jaws to grip said guide ropes, a spring adapted to impel said sliding collars, 115 said spring being normally restrained by tension of the winding rope, a connection between said movable plate and the cage consisting of a rod projecting upward from the cage, and passing loosely through the said plate, and a block through which said rod also passes, jointed rods connecting 120 said block with the aforesaid collars said rod having a shoulder at its upper end to retain 125 said block. 130

4. An automatic safety device for mine cages, lifts, and the like, comprising guide ropes, a movable plate, a pair of jaws mounted at each end thereof and adapted to grip the guide ropes, slideable collars adapted to cause said jaws to grip said guide ropes, a spring adapted to impel said sliding collars, said spring being normally restrained by tension of the winding rope, a connection between said movable plate and the cage consisting of a rod projecting upward from the cage and passing loosely through the said plate, a block through which said rod also passes, jointed rods connecting said block with the aforesaid collars, and rocking frames to assist said rods, said rod having a shoulder at its upper end to retain said block. 35
5. An automatic safety device for mine cages, lifts, and the like, comprising guide ropes, a movable plate, a pair of jaws mounted at each end thereof and adapted to grip the guide ropes, slideable collars adapted to cause said jaws to grip said guide ropes, a spring adapted to impel said sliding collars, said spring being normally restrained by tension of the winding rope, a connection between said movable plate and the cage consisting of a rod projecting upward from the cage and passing loosely through the said plate, a block through which said rod also passes, rods connecting said block with the aforesaid collars, said rod having a shoulder at its upper end to retain said block. 40
6. In combination, a cage or lift, suitable flexible guides therefor, a winding cable connected with the cage, a carrier, jaws mounted on said carrier and embracing said guides, lever mechanism mounted on said carrier for operating said jaws, means carried by said cable and connected with said lever mechanism to support the carrier and operate said jaws to grip but not kink said guides, and a spring device connected with said means and cage and adapted to operate upon breakage of said cable, substantially as described. 45
7. An automatic safety device for mine cages and the like comprising a guide rope, a pair of movable opposed jaws embracing said rope and adapted to grip said guide rope, a slideable collar embracing said jaws and adapted to grip said guide rope, a spring adapted to move said collar into the position to operate said jaws, said spring being normally restrained by tension of the winding rope, operating connections between said spring and said collar, and connections between said spring and winding rope adapted to normally restrain the same. 50
